Frank A. Lewis

UNITED STATES PATENT OFFICE.

FRANK A. LEWIS, OF PORTER TOWNSHIP, VAN BUREN COUNTY, MICHIGAN,
ASSIGNOR OF ONE-HALF OF HIS RIGHT TO GILENS B. LEWIS.

CAR-COUPING.

SPECIFICATION forming part of Letters Patent No. 224,094, dated February 3, 1880.

Application filed August 25, 1879.

To all whom it may concern:

Be it known that I, FRANK A. LEWIS, of Porter Township, Van Buren county, State of Michigan, have invented a new and useful Improvement in Coupling Cars, of which the following is a specification.

My invention is an improvement in car-couplings.

It consists of a hinged lever, with a coupling-pin locked thereto, adapted to swing about a horizontal axis in the upper wall of a draw-head, said lever being moved automatically by contact of the coupling-link with the coupling-pin, and, being released, drops by gravity within the link's slot, as will be hereinafter fully described.

In my drawing, the figure is a sectional view, showing the several parts of the invention and the operation of the same.

Similar reference-letters denote like parts.

Referring to drawing, B is the draw-head or bumper of a railroad-car, having a V-shaped or flaring cavity formed within it for the reception of the coupling-link. A slot is cut in the upper wall of the draw-head, with its front and side walls vertical and its rear wall beveled rearward.

a is a lever or cap hinged or pivoted to the draw-head's sides near the front, which, when in its seat, rests horizontally on the upper surface of the said draw-head. On the upper side of the lever a is a hood or capping, D, inclosing a tongue riveted thereto by rivet e.

C is the coupling-pin, formed with a flanged head, and having an annular groove to receive the tongue g.

In the bottom wall of the draw-head is a notch to receive the end of the coupling-pin when in position.

Between the lower surface of the tongue g and the upper surface of the hinged lever a is

an elastic cushion, f, intended to take a part of the shock received upon the coupling-pin as the draw-heads separate in the act of coupling.

The tongue g, when riveted in the cap or hood D, said cap being secured to lever a, together with the annular groove, serves the purpose of a lock to hold the coupling-pin C as a part of hinged lever a, so that when the coupling-link enters the draw-head it comes in contact with the coupling-pin and throws it backward and up with the hinged lever, as shown by the dotted lines in the drawing. When the link has moved back of said pin the weight of the lever causes the pin to fall within the link's slot. After the tongue g is fixed in the cap or hood D with the rivet, the said cap or hood is placed upon the hinged lever a, with the tongue g in the annular groove of the coupling-pin, and secured to said hinged lever with nails or screws. When the link is drawn upon it comes in contact with the pin C, and causes the flange of the head to bear against the tongue g, and bears the said tongue down upon the cushion f.

I am aware of the patent to Merkle and Merkle, No. 142,713, in which is shown a hinged lever and a coupling-pin hinged thereto, and to such I make no claim.

What I claim as new, and desire to secure by Letters Patent, is—

In combination with a draw-head and coupling-link of a car-coupling, the hinged lever a, pin C, provided with annular groove, and the locking device for said pin with said lever, composed of the hood D and tongue g, as and for the purpose set forth.

FRANK A. LEWIS.
